UNITED STATES PATENT OFFICE.

THOMAS H. COSTELLO, OF CHICAGO, ILLINOIS.

MAP-MOUNTING.

1,233,314.

Specification of Letters Patent. Patented July 17, 1917.

Application filed July 16, 1915. Serial No. 40,171.

To all whom it may concern:

Be it known that I, THOMAS H. COSTELLO, a citizen of the United States, residing at the city of Chicago, in the county of Cook 5 and State of Illinois, have invented certain new and useful Improvements in Map-Mountings, of which the following is a specification.

My invention relates to map mountings 10 and is particularly adapted to be used in connection with those which are mounted on spring rollers and placed in frames, whereby they may be automatically rolled up and protected when not in use. The lower end 15 of such maps heretofore usually has been protected by a rod formed by a plurality of strips of wood semi-circular in cross section between which the lower edge of the map is placed and in which position, it is secured by 20 glue, or nails, or both. The ends of said strips, extend past the edges of the map to engage the frame and limit the movement of the map; but as the map is released or 25 rolled up, the pull of the spring of the roller upon which it is mounted frequently draws the projecting ends of the map stick into violent contact with the sides of the frame. The map sticks are frequently broken, thereby, while the maps are torn from their 30 attachment and frequently destroyed.

It is the object of my invention to provide a composite protecting rod, which may be so securely attached to the edge of the map as to make its displacement in service 35 practically impossible. The device is so simple and cheap that the expense thereof and of the application is practically not greater than that of the ones ordinarily used.

The principles of my invention are illustrated in the drawings, in which Figure 1 40 shows a front elevation of a portion of a map cabinet.

Fig. 2 is a cross section thereof, on the dotted line 2—2.

Fig. 3 shows the inside faces of two identical strips of molding, which together form 45 my improved map stick.

Further describing my invention with reference to the drawings, 1 represents a spring 50 roller attached at the ends 2 and 3 in the well known manner to the side pieces 4 and 5 of a map cabinet and 6, represents the map rolled thereon. My improved map stick is formed of two pieces of molding as 55 shown in Fig. 3. They comprise the body

portion 7 having the outer wall 8 in the segment of a circle. The inner part comprises the flat faces 9 and the reciprocally formed concave portion 10 and convex portion 11. The two pieces of molding represented in 60 Fig. 3 represent strips from the same or an identically formed piece, and it will be noted that when the part designated A is turned over on the part designated B, the convex portion of one strip will be received within 65 the convex portion of the other strip, the two interlocking parts thus forming together a rod which is substantially circular in cross-section. When the lower edge of the map is placed between two pieces of the described 70 molding cut to proper lengths, and the two are pressed together, the lower edge of the map will be forced to follow the interior contour of the pieces and be securely clamped between them. In practice, I prefer to 75 spread glue on the inner faces of the moldings before the map is attached to them and strengthen them or support the hold thereof by the use of screws or nails 12. It will be seen that a perfect attachment of the map 80 stick and the map is thus made. The moldings used can be prepared by the use of but one form of sticker knife, while a stock for manufacturing purpose need consist of but one pattern of material. 85

I claim:

1. A map mounting including a cylindrical body-portion comprising a pair of cooperating identically formed strips having locking faces, each face being formed to provide a tongue and groove defining a continuous reverse curve, and engaging flat surfaces formed on the locking faces of each strip laterally of the reverse curve. 90

2. A map mounting including a cylindrical body-portion comprising a pair of identically formed strips having cooperating locking faces, each face having an S-shaped curve formed centrally thereon, and engaging flat surfaces formed on the remaining 100 portions of the locking faces outwardly of the curve.

In witness whereof I have hereunto set my hand in the presence of two subscribing witnesses this 10th day of July, 1915.

THOMAS H. COSTELLO.
